CLAIM

The ornamental design for a vaporization device as shown and described.

DESCRIPTION

FIG. 1 is a front perspective view of a vaporization device; FIG. 2 is a back perspective view of the vaporization device; FIG. 3 is a top plan view of the vaporization device; FIG. 4 is a front elevation view of the vaporization device; FIG. 5 is a right side elevation view of the vaporization device, a left side elevation view being a mirror image of the right side elevation view and therefore not illustrated in the drawing disclosure; FIG. 6 is a rear elevation view of the vaporization device; and, FIG. 7 is a bottom plan view of the vaporization device. The broken lines in the drawings depict portions of the vaporization device that form no part of the claimed design.
